UNITED STATES PATENT OFFICE

92,154

DESIGN FOR A CONTAINER CLOSURE

Porter E. Stone, Detroit, Mich.

Application January 22, 1934, Serial No. 50,476

Term of patent 3½ years

To all whom it may concern:

Be it known that I, PORTER E. STONE, a citizen of the United States, residing at Detroit, in the county of Wayne, and State of Michigan, have invented a new, original, and ornamental Design for a Container Closure, of which the following is a specification, reference being had to the accompanying drawing, forming part thereof, and in which:

Fig. 1 is a perspective view of an article showing my new design;

Fig. 2 is a front elevational view of the same; and

Fig. 3 is a side elevational view thereof.

I claim:

The ornamental design for a container closure as shown.

PORTER E. STONE.
